INJECTION ENGINE

Arthur W. Pope, Jr., Waukesha, Wis., assignor to
 Waukesha Motor Company, Waukesha, Wis., a
 corporation of Wisconsin

Application September 16, 1938, Serial No. 230,311

1 Claim. (Cl. 123—32)

This invention relates to injection engines, and has to do with injection engines using electrical ignition means, such as glow plugs, for starting.

5 My invention is particularly directed to an engine of what may be termed the high swirl type, in which the fuel-air mixture is caused to rotate or swirl within the combustion chamber at high velocity, during normal operation of the
 10 engine. When starting such an engine, the swirl within the combustion chamber is relatively low and the injected fuel can readily pass across the chamber. I take advantage of that fact by disposing the heating element of a glow plug or
 15 analogous device at the opposite side of the combustion chamber from the injection nozzle, so as to receive the main portion of the fuel spray during the starting cycle. That facilitates starting, eliminating objectionable knocking and
 20 smoking at that time, and after starting the penetration of the fuel spray into the combustion chamber is reduced, due to the relatively high swirl then obtaining in that chamber. Thereafter the injected fuel does not impinge
 25 upon the heating element and the latter is effectively shielded from the violent flame swirl and high temperature within the combustion chamber, being appropriately located to that end. In that manner smooth starting of the engine
 30 is facilitated and the life of the glow plug or analogous device is materially increased.

In the drawing:

Figure 1 is a fragmentary axial sectional view through the upper end of a cylinder and a cylinder head of an engine, showing those parts with which my invention is concerned, certain parts being shown in elevation; and

Figure 2 is a sectional view taken substantially on line 2—2 of Figure 1, on an enlarged scale.
 40 I have disclosed my invention, by way of example, as embodied in an engine comprising a cylinder 5, a piston 6 operating in the cylinder, and a head 7 overlying the cylinder and secured thereover in an appropriate manner, with an intervening gasket 8. The cylinder 5 and the head 7 may be of any suitable construction and are water cooled in a known manner.

Head 7 is provided with a recess approximating in form a segment of a sphere, and receives a
 50 threaded plug 8 provided in its upper end with a recess also approximating a segment of a sphere, the latter recess cooperating with the recess in the head to define a substantially spherical combustion chamber 9. Plug 8 is provided with a restricted throat 10 opening into chamber 9 sub-

stantially tangent thereto, this throat opening at its lower end into the cylinder 5. If desired, piston 6 may be provided, in its upper face, with a recess 11 disposed adjacent the lower end of throat 10, when the piston is on the dwell of its compression stroke, for initially receiving the products of combustion ejected from chamber 9 through throat 10. Plug 8 is further provided with an outer substantially radial recess 12, which receives the inner end portion of a set screw 13 threaded into head 7 at one side thereof, this set screw serving accurately to position plug 8 and secure it in position.

Head 7 is provided with a stepped cylindrical bore 14 extending from an upper surface thereof at an inclination downward and inward at the inner side of combustion chamber 9. Bore 14 receives a glow plug 15 of known type, which threads into the upper portion of bore 14, there being a gasket 16 interposed between a shoulder of plug 15 and a shoulder of bore 14. Body 17 of plug 15 is of less length than bore 14, the portion of the bore below body 17 of the plug defining, with the lower end of the plug body, a pocket 18 which opens into combustion chamber 9, through an opening 19 in a plane of a chord thereof. Plug 15 is further provided with a depending coil 20 supported from body 17 in a known manner, this coil being disposed within pocket 18 with its lower end spaced an appreciable distance above the bottom of the pocket.

An injection nozzle 21 is appropriately mounted in head 7 in a known manner, at the opposite side of combustion chamber 9 from pocket 18. The nozzle may be of any suitable type, that shown being a pintle type nozzle provided with a tip defining an injection port which may be coaxial with the nozzle, line a—b indicating the common axis of the injection nozzle and of the port thereof. The lower end of pocket 18 defines, in the vertical plane of the line a—b, a surface 22 extending outward from the lower end of opening 19 parallel with and substantially in the horizontal plane of line a—b, and a second surface 23 inclined upward and outward from surface 22. The nozzle 21 injects a spray of fuel into combustion chamber 9, along the line a—b.

When starting the engine, during travel of the piston 6 inward on its compression stroke, air displaced from cylinder 5 is forced through throat 10 into combustion chamber 9, in which chamber rotative or whirling motion at relatively low speed is imparted to the air, due to the tangential disposition of throat 10. As piston 6 approaches

its position of maximum compression, injection of fuel is initiated, in a known manner, and may continue until the piston has moved a predetermined distance outward on its working stroke, 5 as is known. The fuel spray passes across the combustion chamber 9, enters pocket 18 through opening 19 and impinges upon coil 20 of the glow plug 15. In this manner pocket 18 is filled with fuel-air mixture surrounding and in contact with 10 coil 20. When piston 6 is at or about its position of maximum compression, the fuel charge is ignited by the heat of compression supplemented by the heat of coil 20, it being understood that glow plug 15 is connected to a suitable source of 15 electrical energy for heating coil 20, in a manner well known in the art. Disposing the heating element of the glow plug in the manner stated facilitates starting and is conducive to smoothness and efficiency in operation.

20 After the engine has been started, and in the normal operation thereof, the swirl within the combustion chamber 9 is much higher than when starting. Consequently, the penetration of the 25 fuel spray into the combustion chamber is materially reduced, and this spray will not reach the opening 19, the high swirl within the combustion chamber being then effective for shielding heating element or coil 20 from the injected fuel. Since coil 20 is outside of chamber 9, within 30 in pocket 18, it is shielded from the violent flame swirl and high temperature within the combustion chamber. The useful life of the glow plug is thus materially increased.

It will be understood, of course, that valve controlled air inlet and burned gas outlet passages are provided, and that suitable means is provided for supplying fuel under pressure to the injection nozzle and timing the injection, as 5 well as regulating the amount of fuel injected per working stroke of piston 6; all as is well known in the art.

I claim:

In an injection engine, a cylinder and a piston 10 operating therein, a head overlying said cylinder, a substantially spherical combustion chamber in said head opening into said cylinder through a restricted passage the upper end of which opens into said combustion chamber at 15 the lower portion of and substantially tangent to one side thereof, an injection nozzle having a tip at said one side of said combustion chamber directly above said passage substantially in the vertical plane of the latter and disposed to inject 20 a stream of fuel across said combustion chamber toward the opposite side thereof, said head having a pocket communicating with said combustion chamber at said opposite side thereof through an opening in a plane of a chord of said 25 combustion chamber and substantially aligned transversely of the latter with the tip of said nozzle and said fuel stream, and electrical ignition means disposed within said pocket and wholly exterior of said combustion chamber.

30
